WELL PACKER

Reuben C. Baker, Coalinga, Calif., assignor to
 Baker Oil Tools, Inc., Vernon, Calif., a corpora-
 tion of California

Application June 23, 1941, Serial No. 399,291

2 Claims. (Cl. 166—12)

This invention relates to well devices, and more particularly to well packers adapted to be anchored in packed off condition within a well casing or liner.

Cement retainers and other forms of well packers are set in packed off condition in casings or liners usually for the purpose of displacing fluids therethrough under pressure for passage into the formation. After the desired displacement operation has been performed, the packer is removed from the casing or liner by drilling, acidizing or other means of disintegration. It is an object of the present invention to provide a well packer apparatus of such design as to leave a lesser quantity of packer material in the casing after the desired operation has been performed, thus facilitating disintegration of the packer and its removal from the casing.

A further object of the invention is to provide an hydraulically operated well packer which cannot be set prematurely. In this connection, the invention contemplates the prevention of premature setting even though circulation is established through the packer.

This invention has other objects that will become apparent from a consideration of the embodiment shown in the drawing accompanying and forming part of the present specification. This form will now be described in detail to illustrate the general principles of the invention, but it is to be understood that such detailed description is not to be taken in a limited sense, since the scope of the invention is best defined by the claims appended hereto.

Referring to the drawing:

Figure 1 is a longitudinal section through a well casing and packer with parts of the latter in retracted position;

Figure 2 is a view similar to Figure 1, with the slips hydraulically expanded against the casing; and

Figure 3 is a view similar to Figure 1, with the packer anchored in packed off condition in the casing.

A tubular well packer body 10 is threadedly connected to a sub 11 forming the lower end of a tubular run-in string A, by means of which the well packer B is lowered through the casing C to the desired setting point. A valve guide or housing 12 is threaded on the lower end of this body 10, being provided with an inwardly directed flange 13 defining an internal groove within which is received an outwardly directed flange 14 of a packing sleeve 15 encompassing the body. The two flanges interlock to prevent inadvertent re-

moval of the lower end of the packing sleeve 15 from its assembled position on the body 10 and in the guide 12.

Similarly, the upper end of the packing sleeve 15 is provided with an external flange 16 cooperating with an internal flange 17 on an expander cone 18 to form an interlock holding the upper end of the sleeve in assembled position in the cone 18 and against the body 10. The cone is 10 slidable on the body and possesses an upwardly converging outer surface 19 cooperable with correspondingly tapered inner surfaces 20 on segmental slips 21, to expand the latter outwardly into engagement with the casing C. The 15 exteriors of the slips are formed as upwardly facing wickers 22 designed to prevent upward movement of the packer when it is anchored to the casing.

The packing sleeve 15 is initially held in retracted position by frangible means 23, such as one or more shear screws, securing the cone expander 18 to the packer body 10. By a similar expedient, the slips 21 are also secured in retracted position by means of shear screws 24 fastening their lower ends to the upper portion of the cone. 25 The upper ends of the slips are engageable with an abutment 25 extending outwardly from a tubular body member 26 threaded on the setting sub 11 to form a separate removable upper extension of the main tubular body 10 of the well 30 packer. The tubular body member 26 and sub 11 may be considered collectively as an upper body member threadedly connected to the lower body member 10.

The slips 21 are releasable for gripping engagement with the casing by hydraulic action, the fluid passing from the tubular string A and the interior of the main body 10 through the ports 27 into the interior of the packing sleeve 15. Leakage of fluid between the body and sleeve is 35 prevented by the opposed lip seals 28, 28 near the ends of the sleeve, which are slidably engageable with the exterior of the body. In the specific tool disclosed, the dropping or lowering of a tripping ball 29 through the tubular string for engagement 40 with a tripping ball seat 30 in the lower end of the guide 12 enables sufficient pressure to be developed within the tubing string A, body 10, and packing sleeve 15 to elongate the latter in an upward direction and exert a longitudinal force capable of shearing the screws 23 fastening the cone 18 to the body, and then the screws 24 attaching the slips 21 to the cone, whereupon the cone is 45 shifted upwardly along the main body 10 and adjoining removable body member 26 and within 50 the slips. Since these slips cannot move upward-

ly because of their engagement with the abutment 25, the upward longitudinal sliding of the cone expander 18 along the bodies forces them radially into anchoring engagement with the casing C. The taking of an upward strain on the tubing string A and body 10 thereafter compresses the packing sleeve 15 to effect a seal between the main body 10 of the packer and the wall of the casing.

Due to the embedding of the wickers 22 in the casing, neither the slips 21 nor the cone 18 wedged therein can move upwardly during this packing off operation, which means that the main body 10 is moved upwardly with respect to the cone to permit the locking engagement of a split, contractile lock ring 31 provided in an internal groove 32 in the cone with one of the annular ratchet teeth 33 formed on the exterior of the main packer body, thus preventing return downward movement of the body 10 with respect to the cone 18 and positively securing the slips 21 and packing 15 in firm engagement with the casing C.

In view of the fact that the upper body member 26 and its abutment 25, as well as the sub 11, serve no useful purposes after the slips 21 have been set and the packing sleeve 15 compressed, they need not remain in the well bore after the desired well operation has occurred. Accordingly, rotation of the tubing string A to the right will effect an unscrewing of the sub 11 from the main packer body 10, whereupon elevation of the tubing string withdraws both the sub and the removable body 26 and abutment 25 from the well bore, leaving the remainder of the well packer anchored in the casing. This operation can readily occur since the slips 21 and cone 18 are below the upper removable body member 26 after the packer is fully set in packed off condition within the casing.

The well packer can be used advantageously merely by incorporating the parts heretofore described. The construction disclosed in the drawing includes additional features, whereby passage of fluid under pressure from the interior of the main body 10 into the packing sleeve 15 is positively controlled from the surface of the bore by either opening or closing the ports 27. The control device consists of a sleeve valve extension 34 depending from the sub 11, which is slidably engageable with opposed packing seals 35, 36 disposed in internal grooves 31, 38 in the body at opposite sides of its ports. The position of this extension 34 with respect to the seals is determined by rotating the tubular string A in either direction. Since left hand threads are preferred in connecting the sub 11 with the main body 10 and removable body 26, rotation of the tubular string to the right elevates the depending control sleeve 34 and moves its lower end 34a above the lower seal 36, permitting fluid under pressure to pass from within the sub 11 around its lower end, through the space between the extension 34 and packer body 10, and into the ports 27 for expansion of the elongate packing 15. Conversely, rotation of the tubular string to the left effects a lowering of the sub 11 and a closing of the ports by engagement of the exterior of the control sleeve 34 with both slidable ring seals 35, 36.

In order for rotation of the sub 11 to occur with respect to the body 10 of the packer in controlling the ports 27, the body 10 is prevented from rotating through the agency of the upper body 26, which is releasably coupled to the main

body by means of releasable locking studs 39 secured to and depending from the upper body for normal reception within sockets 40 at the upper end of the main body member. Friction members 41 are disposed within elongate slots or grooves 42 formed at spaced points around the removable body 26, being urged outwardly into engagement with the wall of the casing by springs 43 received within sockets 44 in each member and bearing against the bottoms of the grooves 42. Outward movement of these friction members 41 under the influence of the springs is limited by the rings 45 secured to the removable body 26 by screws 46 and overlapping into the slots 42 to engage the reduced ends 41a of the friction members.

In use, the wall of the casing C forces the friction members 41 inwardly against the action of the springs 43, thereby creating enough drag to hold the upper member 26 from rotating, and correspondingly preventing rotation of the main body 10, because of the coupling 39, 40. Rotation of the tubular string A and its sub 11 can therefor occur without rotary movement of either the removable body member 26 or the main body member 10, although the friction members 41 do not prevent longitudinal translation of the packer B in the casing. To preclude sand or other foreign material from passing between the removable body 26 and the sub 11, a seal 47 may be provided in a groove at the upper end of the removable body for slidable engagement with the exterior of the sub.

For the purpose of preventing return flow of fluids through the packer after it has been anchored in packed off condition in the casing, a back pressure valve may be employed. As disclosed in the drawings, this consists of a ball 48 adapted to move upwardly to engage a valve seat 49 formed at the lower end of the main body 10. This valve seat may include a rubber or other elastic sealing ring 50 to prevent leakage around the ball.

When running the tool B in the well casing with the various members in retracted position (Figure 1), the sub 11 is threaded into both bodies 10, 26 of the packer to its fullest extent, in which position spaced fingers 51 depending from the lower end of the sleeve 34 hold the valve ball 48 in a downward position removed from its cooperable seat 49. Fluid may therefore pass freely in both directions through the well packer B, between the fingers 51 and around the ball 48. Downward movement of this ball is limited by its engagement with the spaced ribs 52 extending inwardly of the guide member 12, the fluid by-passing around the ball and between these ribs for exit through the tripping ball seat 30 at the lower end of the guide. When the sub 11 is in this position, fluid under pressure is also prevented from entering the body ports 27 to expand the packing sleeve 15 and set the packer. As a result, fluid may be pumped downwardly through the tubular string and well packer for the purpose of performing washing, circulating, or other operations within the well bore without fear of prematurely tripping and setting the well packer.

Whenever the packer B is to be set, the tripping ball 29 is lowered or pumped down the tubular string A and through its sub 11 for bypassing around the ball 48 and between the inwardly extending ribs 52 to engage its companion seat 30. Turning of the tubular string a sufficient number of times to the right elevates

the string and its sub until the lower, circumferentially continuous end 34a of the sleeve 34 is above the lower sealing ring 36 (Figure 2). This action occurs since the main body 10 is prevented from turning by the friction members 41. The building up of pressure within the tubular string to the desired degree elongates the packing sleeve 15 to set the slips 21 in the manner heretofore described, after which an upward strain may be taken on the tubular string to compress the packing member 15 between the body 10 and casing C and effect an annular seal therebetween (Figure 3).

An increase in the pressure within the tubing string above a predetermined value shears the screw 53 holding the tripping ball seat 30 in the lower end of the guide or valve housing 12, and enables the seat 30 to be pumped from the packer. The desired cementing operation, under pressure, or other operation, may now take place within the casing in a known manner, return flow of the fluid from below the packer being prevented by engagement of the back pressure ball 48 with its seat 49.

If desired, after the slips 21 have been set and the packing sleeve 15 compressed, the pressure within the packing sleeve may be retained and prevented from dissipating, if the pressure in the tubular string is subsequently decreased, by turning the tubular string A in the proper direction, as to the left, to shift the sub and its sleeve 34 downwardly again until its lower end 34a again seals over the lower sealing ring 36. The fluid under pressure will now be trapped within the packing sleeve 15 and cannot be dissipated.

After the cementing, acidizing, or other operation in the well bore has been completed, the tubular string A may be turned to the right, to elevate the sub 11 with respect to the body, and permit the back pressure ball 48 to engage its cooperable seat 49 at the lower end of the main body 10. A continuation of this rotation unscrews the sub from the main body 10, after which upward elevation of the tubing string A lifts the coupling studs 39 from the sockets 40 and removes the upper body member 26 together with the friction members 41 to the surface of the bore, since the sub 11, although unthreaded from the main body 10, is still in threaded engagement with the removable body 26. As a precaution against unscrewing of the sub 11 from this upper body 26, it is provided with an inwardly extending abutment 54 engageable with a corresponding stop 55 at the upper threaded end of the sub. This not only limits the extent of threading of the sub upwardly into the upper body member, but also insures against complete disconnection between the two.

The packer body elements are preferably made of readily drillable materials, such as cast iron, aluminum alloy, or magnesium alloy, to enable the elements remaining in the casing to be readily removed by a drilling operation, acidizing, or any other suitable expedient.

It is apparent that a well packer has been devised which leaves a lesser quantity of metal in the well casing to be removed. This not only effects a savings in the cost of manufacturing devices of this character, but also results in a savings to the operator, who can dispose of the packer from the well bore with less effort and in a shorter period of time. The removable body 26 with its abutment 25, friction members 41 and the sub 11 can be employed over and over again. Moreover, premature setting of the packer when circulation becomes essential prior to its setting is positively prevented, which offers assurance of setting the packer only at the desired point in the well casing, and not at any other point therein.

I claim:

1. A device of the character described including separate upper and lower tubular body members, means coupling said members together against relative rotation but permitting longitudinal separation therebetween, slips engageable with said upper body member when in retracted position, fluid actuated means slidable along said upper body member for moving said slips radially into gripping engagement with a well casing within a well bore, said lower member having ports for directing fluid under pressure from said lower body member to said fluid actuated means, tubular means threaded attached to both of said body members and operable from the top of said well bore for controlling passage of fluid through said ports so that such fluid can operate said fluid actuated means, and friction means on said upper body member cooperable with said casing for resisting rotary movement of said body members to permit rotation of said tubular means with respect thereto.

2. A device of the character described adapted to be lowered in a well casing on a tubular string, including separate upper and lower body members, means releasably connecting said body members together, said upper body member having an abutment, slips engageable with said upper body member when in retracted position, a conical expander for anchoring said slips to said casing, a normally retracted packing sleeve surrounding said lower body and having its upper end fixed to said conical expander, and means for directing fluid under pressure from said lower body member to said packing sleeve to elongate the latter and shift said conical expander upwardly along said upper body member within said slips for moving them against and along said abutment radially into gripping engagement with said casing, said body members being movable longitudinally in an upward direction after engagement of said slips with said casing to expand said packing sleeve against said casing and elevate the upper body member away from both said slips and conical expander to enable said upper body member to be disconnected from said lower body member.

REUBEN C. BAKER.
